(57) **CLAIM**

The ornamental design for a heel incision safety lancet, as shown and described.

DESCRIPTION

FIG. 1 is a front bottom left side perspective view for a heel incision safety lancet, showing our new design;

FIG. 2 is a rear top right side perspective view of FIG. 1 thereof;

FIG. 3 is a front elevational view of FIG. 1 thereof, the rear elevational view being a mirror image;

FIG. 4 is a left side elevational view of FIG. 1 thereof;

FIG. 5 is a right side elevational view of FIG. 1 thereof;

FIG. 6 is a top plan view of FIG. 1 thereof; and,

FIG. 7 is a bottom plan view of FIG. 1 thereof.

The broken lines indicate unclaimed portions of the heel incision safety lancet and form no part of the claimed design.
